DIMMER DEVICE FOR HEADLIGHTS

Filed April 11, 1927

INVENTOR.
STANLEY J. GRASLEWICZ.
BY HIS ATTORNEYS.

William K. Williamson

UNITED STATES PATENT OFFICE

STANLEY J. GRASLEWICZ, OF MINNEAPOLIS, MINNESOTA

DIMMER DEVICE FOR HEADLIGHTS

Application filed April 11, 1927. Serial No. 182,710.

This invention relates to a headlight adapted to be used on vehicles such as automobiles and particularly to a dimming means for such a headlight. As is well known, there is often a very objectionable glare from the headlights on such vehicles. This glare is particularly objectionable to drivers approaching such headlights and often obscures the approaching vehicle and prevents the approaching driver from properly seeing the road.

It is an object of this invention, therefore, to provide a simple, efficient and easily operated means for controlling the lamp in the headlight so that there will be no glare from the latter.

It is also an object of this invention to provide a headlight having a lamp therein and a dimming means in the form of a sleeve of translucent material movable relatively to said lamp so as to embrace the same at certain times and diminish the reflected light therefrom so that the glare from the headlight is eliminated, said sleeve being held locked in its dimming position together with electrically operated means for relatively moving said sleeve and lamp and unlocking said sleeve.

It is more specifically an object of the invention to provide a headlight having a lamp therein and a substantially cylindrical shield or sleeve movable relatively thereto so as to surround the lamp at certain times and diminish the reflected light therefrom, electro-magnetic means being provided to relatively move said lamp and shield, locking means being provided to hold said shield in dimming position, and electro-magnetic means being provided to unlock said shield.

These and other objects and advantages of the invention will be fully set forth in the following description made in connection with the accompanying drawings, in which like reference characters refer to similar parts throughout the several views and in which:

Fig. 1 is a horizontal central section through the device; and

Fig. 2 is a vertical section taken on line 2-2 of Fig. 1 as indicated by the arrows.

Referring to the drawings, a headlight is shown having the outer casing 5 in which is supported the inner casing or reflector 6. The usual lamp socket 7 is provided, mounted in a flange bearing 8 secured to the casing 5 by the screws 9. The usual lamp bulb 10 is mounted in the socket 7 and projects axially of the reflector 6. A bracket 12 is secured to the rear of the casing 5 by the screws 9 having a rearwardly projecting hollow cylindrical portion or sleeve 12^a. The member 12 has a pair of holes 12^b adjacent opposite sides thereof and tubes 13 are disposed in said holes and held therein by the set screws 14. A pair of rods 15 extend through the tubes 13 and through alined holes in the casing 5 and reflector 6, said rods being threaded at their front ends to receive clamping nuts 16 between which is clamped an annular member 17 having a forwardly projecting frusto-conical flange receiving a frusto-conical sleeve or shield 18 secured therein.

The sleeve 12^a, lamp socket 7 and shield 18 are all co-axially arranged. The rods 15 are also threaded at their rear ends to receive clamping nuts 19 between which is secured a circular plate 20. Secured to the plate 20 is a tube or spool 21 which projects inwardly from said plate. The plate 20 has a pair of slots 20^a extending therethrough for a purpose to be later described. Said tube carries or has wound thereon a coil 22 forming a solenoid coil and it will be noted that the opening through the tube 21 is slightly greater than the diameter of the sleeve 12^a. The member 12 also has secured thereto by the screws 14 an outer casing 23 enclosing tubes 13, the rods 15 and the plate 20, said casing fitting over the outer side of member 12. The casing 23 is closed at its rear end and has members 24 secured thereto at spaced points, which preferably will be made of fiber or rubber.

Small fiber or rubber washers 24^a are also placed on the rods 15 at the ends of tubes 13 and also form bumper members. A coiled spring 25 is disposed between the plate 20 and the rear end of sleeve 12^a. A tube or spool 26 is disposed within the outer end of sleeve 12^a and has wound thereon a solenoid

coil 27. The sleeve 12^a has a member 28 secured to and spanning its rear end to which are pivoted bell crank members 29 formed with hooks at their outer ends and having their inner ends pivoted by a common pivot to a stem or pin 30 which at its inner end is threaded and secured in a cylindrical member 31 forming the core of solenoid coil 30 and having an enlarged stud 31^a at its inner side 10 between which stud and the end of spool 26 is disposed a coiled spring 32. Conductors 33 extend to the lamp socket 7, coil 22 and the coil 27 respectively. The conductor extending to the coil 22 will be disposed in the bottom of casing 23 and will be quite flexible. The conductor 33 extending to the lamp socket will as usual be connected to the lamp or headlight switch. The conductors 33 extending to the solenoids 22 and 27 will be connected to some convenient switches such as push buttons disposed in convenient position for manipulation by the driver. One side of the circuits formed by the conductors 33 will preferably as usual be grounded to the frame of the machine or to the casing 5 of the headlight. The member 12 will be of soft iron or steel, while the rods 15 and the spring 25 will preferably be made of brass.

In operation the parts will normally occupy the position shown in full lines in Fig. 1. At this time as shown the shield 18 which is made of frosted celluloid or some similar translucent material will be substantially in the rear of the lamp bulb 10. When it is desired to dim the headlight, as when approaching another car, the driver will press the button controlling the solenoid 22. This solenoid will then be energized and will be attracted to the sleeve 12^a. As the sleeve is fixed, the coil 22 will move over the sleeve, thus carrying with it the plate 20 and the rods 15. The rods thus move the shield 18 forwardly to the dotted line position shown in Fig. 1. As the plate 20 approaches the end of the sleeve 12^a the hook arms of levers 29 pass into the slots 20^a and engage over the inner edges of the said slots as indicated in dotted lines in Fig. 1. The shield when in its forward position intercepts practically all of the rays which pass from lamp 10 to the rear portion of the reflector 6. The rays are not entirely cut off, as the member 18 is, as stated, translucent. Practically all of the reflected light, however, is cut off so that the glare is eliminated from the headlight. At the same time the direct rays from lamp 10 can pass out through the front of the headlight and give ample illumination for driving purposes. When it is desired to place the headlight in normal position, the operator will press the button controlling the solenoid 27. This coil 27 will then be energized and the core 31 will be drawn thereinto against the tension of spring 32. As core 31 moves into the coil it presses on the inner ends of levers 29 and the

hooked ends thereof are then moved outwardly, thus releasing the plate 20. Spring 25 which was compressed upon movement of the coil 22 thus retracts plate 20 and through the rods 15 moves the shield 18 to its normal position. The members 24 and 24^a are engaged by the nuts 19 in the forward and rearward movement of coil 22 and act as bumpers.

From the above description it is seen that applicant has provided a very simple and efficient headlight with dimming attachment. The parts are all quite compact, simple in construction and easily installed, and operated. The operating parts are also all enclosed in the casing 23 and are thus well protected. The device will have a high degree of utility for the purpose intended.

It will, of course, be understood that various changes may be made in the form, details, arrangement and proportions of the parts, without departing from the scope of applicant's invention, which, generally stated, consists in a device capable of carrying out the objects above set forth, in the novel parts and combinations of parts disclosed and defined in the appended claims.

What is claimed is:—

1. A headlight with a dimming attachment having in combination, a casing, a reflector within said casing, a lamp socket disposed therein, a lamp in said lamp socket, a tubular shield normally disposed substantially at the rear of said lamp and in front of the reflecting surface of said reflector, a pair of small parallel rods carrying said shield and extending through said reflector, a member of magnetic material secured to the rear of said casing, means carried by said member in which said rods are movable, said member having a central hollow sleeve coaxially arranged with said lamp socket and lamp, an electro-magnetic coil movable over said sleeve to which said rods are connected, said coil being movable over said sleeve when energized to move said shield to dimming position substantially over said lamp, a locking means for holding said shield in dimming position and an electro-magnetic coil within said sleeve adapted to release said locking means and means for moving said shield to normal position.

2. A headlight with a dimming attachment having in combination, a reflector, a lamp socket therein, a lamp disposed in said socket, a tubular shield normally disposed in the rear of said lamp and always disposed in front of said reflector, means for moving said shield to a dimming position substantially over said lamp, a plate secured to said means, a pair of locking levers engageable with said plate to hold said shield in dimming position, an electro-magnetic coil, a plunger movable in said coil and pivotally connected to said levers to swing the same to releasing po-

sition to release said shield and means for moving said shield to normal position.

3. A headlight with a dimming attachment having in combination, a reflector, a lamp support, a lamp therein, a rigid tubular shield of translucent material at all times in front of said reflector and normally disposed in the rear of said lamp, supports for said shield comprising small rods passing through said reflector, an electro-magnetic coil connected to said lamp support and shield, said lamp socket and shield being relatively movable when said coil is energized to position said shield substantially over said lamp, a spring 10 against the tension of which said shield is movable, a locking means for holding said shield in dimming position, and additional electro-magnetic means for releasing said locking means to permit said spring to move 15 said shield to normal position.

4. A vehicle headlight comprising a dimming attachment having in combination, a reflector, a lamp socket therein, a lamp bulb in said socket, a rigid translucent tubular shield of much less length than the diameter 25 of said lamp bulb, spaced rods of small transverse dimension carrying said shield extending through the rear of said reflector, said shield being normally in position in the rear 30 of said lamp bulb and in front of said reflector whereby it obstructs no light in front of said lamp bulb, and light may be reflected from the lamp through the opening in said shield, means controlled by the operator for 35 moving said rods to position said shield substantially centrally over said lamp bulb to obstruct the direct rays therefrom from a large portion of said reflector, locking means for holding said shield in said latter position, 40 and additional electro-magnetic means controlled by the operator for releasing said locking means, and means for returning said shield to normal position.

5. A vehicle headlight comprising a dimming attachment having in combination, a reflector, a lamp supported therein, a rigid annular shield for said lamp, normally disposed in front of said reflector and in the rear of said lamp, supporting means for said 45 shield extending through said reflector and interrupting only a small portion of the surface thereof, means in the rear of said reflector connected to said shield for moving the same bodily to a position surrounding the filament of said lamp with its rear edge a substantial distance from the reflector, and means for returning said shield to normal position.

6. A vehicle headlight comprising a dimming attachment having in combination, a reflector, a lamp stationary relative to said reflector, a short rigid tubular shield of translucent material for said lamp normally disposed in front of said reflector and in the rear of said lamp, an electro-magnetic coil in 60 the rear of said reflector and concentrically

arranged in relation to said lamp and shield, supporting rods for said shield disposed at diametrically opposite sides thereof carried by said coil, said shield and rods being movable with said coil when the latter is energized to move said shield substantially over said lamp, a spring against the tension of which said shield is movable, a locking means for holding the shield in said latter position and additional electro-magnetic means adapted to be operated by the driver of the vehicle for releasing said locking means to permit said shield to move to normal position, said reflector extending in the rear of said shield whereby light may be reflected forwardly 70 through the opening in said shield when in normal position.

In testimony whereof I affix my signature.
STANLEY J. GRASLEWICZ.
